DESIGN FOR A BURIAL CASKET.

WILLIAM L. LOCKHART AND J. C. SEELYE, OF EAST CAMBRIDGE, MASSACHUSETTS.

Design No. 2,510, dated November 27, 1866.

SPECIFICATION.

TO ALL WHOM IT MAY CONCERN:

Be it known that we, WILLIAM L. LOCKHART and J. C. SEELYE, both of East Cambridge, in the county of Middlesex, and State of Massachusetts, have originated and produced a new design for a Burial Casket, of which the following is a full and clear description, reference being had to the accompanying drawings making part of this specification.

In the manufacture of coffins, the mere plain, box-shaped article is gradually being discarded for caskets, in which some attention is given to outward ornamentation, replacing the rigid straight corners by a configurated outline. It is to such ornamental construction that this invention relates, or to a design for a moulding for surmounting the sides or walls of the coffin or burial casket. This design, which is shown in the drawings, consists of a straight moulding, *a*, applied to the top of each side and end wall, *b*, the moulding being surmounted by the cap or cover, *c*, the drawings representing a side elevation and an end elevation of the coffin or casket.

We claim the design for a burial casket, as shown and described.

WILLIAM L. LOCKHART,
J. C. SEELYE.
